Primary Examiner — Susan E Krakower(74) *Attorney, Agent, or Firm* — Patterson Thuente Christensen Pedersen, P.A.(57) **CLAIM**

The ornamental design for a short thumb spica brace, as shown and described.

DESCRIPTION

FIG. 1 is a front perspective view of a short thumb spica brace of the present invention;

FIG. 2 is a front perspective view from the opposing angle;

FIG. 3 is a side perspective view; and,

FIG. 4 is a rear perspective view.

It is understood that the broken lines on the surface of the claimed design indicates stitch lines which form part of the claimed design, while the circular elements on the surface of the claimed design indicated with broken lines form no part of the claimed design.
